UNITED STATES PATENT OFFICE.

CHARLES B. BROWN, OF CHICAGO, ILLINOIS.

VEHICLE-AXLE.

SPECIFICATION forming part of Letters Patent No. 399,013, dated March 5, 1889.

Application filed October 1, 1888. Serial No. 286,883. (No model.)

To all whom it may concern:

Be it known that I, CHARLES B. BROWN, a citizen of the United States, residing in Chicago, in the county of Cook and State of Illinois, have invented a new and useful Improvement in Wagon-Axle Bars, of which the following is a specification.

My invention relates to iron axles for wagons.

10 The object of my invention is to provide an axle-bar of a simple, light, and strong construction.

In the accompanying drawings, which form a part of this specification, and in which similar letters of reference indicate like parts, Figure 1 is a side elevation of a device embodying my invention. Fig. 2 is a perspective view of a short section of the axle-bar, showing the same before its ends are shaped to enter the skein. Fig. 3 is a plan view showing one end of the finished axle-bar. Fig. 4 is a cross-section on the line 4 4 of Fig. 3, and Fig. 5 is a cross-section on line 5 5 of Fig. 3.

In said drawings, A represents an iron bar having three webs, a , a' , and a^2 , with two channels, a^3 , a^4 , between them. At each end of the axle A the two outer webs, a , a^2 , are squeezed into contact with the middle web, a' , and drawn out to form the solid tapering end a^5 of the axle, which fits in the skein B. This tapering solid end of the axle a^5 is preferably rectangular in cross-section. The extreme end of the axle is drawn out into a round rod, a^6 , which is furnished with screw-threads a^7 to receive the nut b. The webs a , a^2 at the point where they are crowded together are somewhat curved, as shown at c. The outer walls of the webs a , a^2 are at right angles to the bottom face of the bar A; but the webs a , a^2 , as well as the middle web, a' , are somewhat tapering in cross-section, as is clearly shown in Fig. 4. These webs may be formed upon the bar by rolling; or, if desired, the middle web may be welded in place between the two outer webs. The middle web serves to give, in connection with the two outer webs, great strength to the axle, and also to give sufficient body to properly fit within the socket of the skein. It also strengthens the axle at 45 the inner end of the skein, which is the point where ordinary axles customarily break.

I hereby disclaim the devices shown and described in Patent No. 36,914, to Post, of November 11, 1862; No. 243,730, to Schreyer, of July 5, 1881, and No. 308,531, to Therien, of November 25, 1884.

In my invention the channel-bar axle is provided with three webs extending from one end to the other, the three webs being squeezed or forced together at each end of the bar to form the tapering ends or spindle portion of the axle. By reason of the central web the hollow space between the outer webs is diminished, so that the two outer webs when crowded against this inner central web will form a gradual curve, as indicated in Fig. 3 of the drawings, and give this shank portion of the axle, which unites the main or middle part to the spindle part, a form of great strength to resist both vertical and lateral strains. This is a matter of the greatest importance in the practical construction of the axle, because it is this shank portion of the axle between the end of the skein and the hound-bolt wherein the axles usually spring or break. This third or central web also at the same time strengthens the entire axle. Where, for example, as in the Therien patent, No. 308,531, the axle is made of a channel-bar having but two webs, the axles I, find from practical experience in their manufacture and use, are always giving out either by becoming sprung or broken at the shank portion. This is due to the fact that the hollow space between the two webs of the Therien patent axle is necessarily so great that the two webs thereof when crowded together to form the solid spindle portion of the axle necessarily form a sharp bend or shoulder at the point where the spindle portion unites with the axle. This will be apparent to those skilled in the art from a mere inspection of Figs. 2 and 3 of the Therien patent. In endeavoring to remedy this deficiency or defect in the Therien axle I made this present improvement, my first experiment being to weld two short central webs in the Therien axle, one near each end thereof or at the shank portion thereof, so that the outer webs might be crowded against the central short webs without forming an abrupt bend or shoulder. By further experiments I found that still better results could be produced by form-

ing the axle with a central web throughout its entire length. Where the three webs are crowded together, as indicated at Fig. 3 and in the cross-section, Fig. 5, great strength is given to the solid tapering spindle portion of the axle, the effect being similar, or on the same principle as applies where a number of boards set edgewise are bolted or secured together.

10 Another difficulty which I found in the practical construction of the Therien axle was the frequent breakage of the cast skeins which fit therein, when the axles were in use, by reason of the knife-like bearing of the two 15 widely-separated webs of the Therien axle on the shell of the skein. My central web divides the space between the two outer webs, and the three webs combined give in effect a flat bearing upon the shell of the skein very 20 similar to what it would be if the axle were made of a solid instead of a channel bar.

I claim—

1. The rolled channel axle-bar having three webs extending from one end of the axle to the other, said webs being squeezed together 25 at the ends of the bar to form tapering ends, said tapering ends uniting with the middle part of the axle on gradual curves without forming abrupt bends or shoulders, substantially as specified.

2. The combination, with an axle-bar having three parallel vertical webs squeezed together at the ends of the axle, of axle-skeins fitting upon the tapering ends of said axle-bar, said tapering ends uniting with the middle 35 part of the axle on gradual curves without forming abrupt bends or shoulders, substantially as specified.

CHAS. B. BROWN.
